Primary Examiner — Cynthia M Chin*(74) Attorney, Agent, or Firm* — Knobbe, Martens, Olson & Bear, LLP**CLAIM**

The ornamental design for a kart, as shown and described.

DESCRIPTION

FIG. 1 is a front perspective view of a kart, which embodies my design.

FIG. 2 is a front view of the kart of FIG. 1.

FIG. 3 is a rear view of the kart of FIG. 1.

FIG. 4 is a left side view of the kart of FIG. 1.

FIG. 5 is a right side view of the kart of FIG. 1.

FIG. 6 is a top view of the kart of FIG. 1.

FIG. 7 is a bottom view of the kart of FIG. 1; and,

FIG. 8 is a cross-sectional view of the kart of FIG. 1 as indicated in FIG. 2.

Broken lines are used to illustrate features of the kart which form no part of the claimed design.
